UNITED STATES PATENT OFFICE.

GEORGE PURVIS, OF DETROIT, MICHIGAN.

BLOW-OFF FOR BOILERS.

1,098,836.

Specification of Letters Patent. Patented June 2, 1914.

Application filed August 6, 1913. Serial No. 783,249.

To all whom it may concern:

Be it known that I, GEORGE PURVIS, a citizen of the United States of America, residing at Detroit, in the county of Wayne and State of Michigan, have invented certain new and useful Improvements in Blow-Offs for Boilers, of which the following is a specification, reference being had therein to the accompanying drawings.

10 This invention relates to a blow-off for boilers whereby the sediment that frequently collects at the bottom of the shell may be removed at will of the operator without disturbing the working conditions of the 15 boiler. The invention also includes means for increasing the circulation of the boiler.

The invention consists in the matters hereinafter set forth and particularly pointed out in the appended claims.

20 In the drawings, Figure 1 is a view in longitudinal vertical section of one type of boiler equipped with a blow-off that embodies features of the invention; Fig. 2 is a view in transverse section thereof; Fig. 3 25 is a plan view in detail of the blow-off and adjacent portions of the boiler; Fig. 4 is a view in detail of the front end of a valve casing; Fig. 5 is a view in transverse section through a valve casing; Fig. 6 is a view in 30 longitudinal section through the casing; Fig. 7 is a view in detail of a suction nozzle; and Figs. 8 and 9 are views in detail of an outlet member of a circulating pipe.

Referring to the drawings, a shell 1 of a 35 boiler, which as herein indicated is of the Scotch type, has a longitudinal member 2 near its base which may be either a stay rod as herein shown or a guide that is inserted for this special purpose. A valve stem 3 40 extends through a suitable stuffing box 4 in parallel relation to the stay rod or guide member 2 and enters through a packing gland 5 into a valve casing 6. The latter is connected to an outlet pipe 7 through the 45 drum of the boiler by means of suitable fittings 8 arranged with telescoping, swiveling, or like flexible connections which permit movement of the casing in the general direction of the guide member 2. A plurality of 50 suction pipes extends from suitable ports 9 in the casing with suction nozzles 10 at their outer ends. The pipes are so disposed that the nozzles are arranged at intervals along the lower portion of the boiler, those that are 55 farthest from the valve casing being supported by hangers 11 with guide wheels 12

that run on the stay or guide member 2. Each suction nozzle preferably consists of a substantially rectangular casing having an open bottom with serrated margins to its 60 walls as indicated at 13, which conform in a general way to the curvature of the boiler shell and act as agitators to stir up any sediment that is collected there.

A disk 14 on the stem 3 within the valve 65 casing is provided with a single port 15 which may be brought into register with any one of the ports 9 that opens into the discharge nozzle pipes by rotating the stem through suitable means as for example, a 70 hand wheel 17 which may have suitable index means for indicating which suction pipe is open. A suitably disposed spring member 18 may be used to hold the closure to seat.

A circulating pipe 19 having a down-turned end portion that opens near the lower portion of the boiler shell discharges through an inlet opening 20 in the casing that is controlled by the closure 14 through a regulating port 21. An upright pipe 22 80 in the circulating system of the device leads from a second opening 23 in the casing that is controlled by a second port 24 in the closure so that it is opened simultaneously with the opening 20 through the port 21 at a time 85 when the ports 9 are sealed by the closure. A suitable fitting 25 is secured on the upper end of the upright pipe 22 and is arranged to increase the circulating effect by bringing as much an area of the discharge member 90 into contact with the hot water at this point as may conveniently be done. Preferably the fitting consists of a nipple 26 discharging through the arm 27 of the spider into the annular space formed by an inner cylinder 95 28 and an outer cylinder 29 which are substantially continuations of the inner and outer walls respectively of the spider arms. This form of fitting allows the walls to contact inside and out with the hot water at this 100 point and thereby increases the draft through the pipe 22.

In operation, the blow-off suction nozzles are opened successively by proper manipulation of the valve stem and closure and during the use of each, the valve stem is reciprocated so that the entire surface of the boiler that may be traversed by each nozzle is thoroughly swept thereby and the sediment stirred up and drawn into the nozzles. 105 Because of the selective action of the valve, one nozzle only at a time is in use and this 110

insures a proper exhaust and consequent velocity through the discharge pipe to produce the necessary results. As an adjunct to the proper operation of the blow-off the 5 circulating pipes aid in preventing any still pockets in the water and are in action whenever the blow-off nozzles are closed.

It is understood that the disposition of the several parts is varied to suit the requirements of any type of boiler to which the 10 device may be adjusted and that the manner of suspension of the nozzles may be arranged to utilize any parts of the boiler that could possibly be used for this purpose.

15 Obviously, changes in the details of construction may be made without departing from the spirit of my invention and I do not care to limit myself to any particular form or arrangement of parts.

20 What I claim is:—

1. A blow off for a boiler having a set of suction members each arranged to sweep a portion of the interior of the boiler shell, an extensible outlet pipe through the boiler 25 shell, a valve for selectively throwing the suction members into communication with the outlet pipe, and means exterior to the boiler for manipulating the valves and suction members.

30 2. A blow off for a boiler having a set of suction members, nozzles on the members arranged to sweep and mechanically dislodge matter from a portion of the interior of the boiler shell, an extensible outlet pipe, 35 a valve for selectively throwing the suction members into communication with the outlet pipe, and means exterior to the boiler for manipulating the valves and suction members.

40 3. A blow off for a boiler having a set of suction members, the nozzles of which are arranged to sweep a portion of the interior of the boiler shell, means for supporting the suction members on a member of the 45 boiler substantially parallel to the path of motion of the members, an outlet pipe through the boiler shell that is longitudinally extensible within the shell, a valve for selectively throwing each of the suction 50 members into communication with the outlet pipe, and means exterior to the boiler for operating the valve and moving the suction members.

55 4. The combination with a boiler, of a blow off having a set of suction members, the nozzles of which are arranged to sweep a portion of the interior of the boiler shell, an outlet pipe through the shell longitudinally extensible within the shell, a valve 60 having a single outlet in communication with the outlet pipe, and inlets each in communication with the suction member, water circulating means having an inlet adjacent the portion of the boiler shell affected by the 65 suction members that is controlled by the

valve, and means exterior to the casing for operating the valve to cut off the circulating member and simultaneously throw any one of the suction members into communication with the outlet pipe.

70 5. A blow off for a boiler comprising a valve having a single outlet and a plurality of inlets, suction members each connected to an inlet of the valve whereby each may be thrown into communication severally with the outlet, means exterior to the boiler for manipulating the valve and reciprocating the same within the boiler, and an outlet pipe through the boiler shell having extensible connections with the outlet of the so valve.

75 6. A blow off for a boiler comprising a valve having a single outlet and a plurality of inlets, suction members each connected to an inlet of the valve whereby each may be thrown in communication severally with the outlet, means exterior to the boiler for manipulating the valve and reciprocating the same within the boiler, an outlet pipe through the boiler shell having extensible 90 connections with the outlet of the valve, and nozzles on the suction members adapted to mechanically agitate matter on the interior of the shell when the valve is reciprocated.

80 7. A blow off for a boiler comprising a valve having a single outlet and a plurality of inlets, suction members each connected to an inlet of the valve whereby each may be thrown in communication severally with the outlet, means exterior to the boiler for manipulating the valve and reciprocating the same within the boiler, an outlet pipe through the boiler shell having extensible connections with the outlet of the valve, 95 nozzles on the suction members adapted to mechanically agitate matter on the interior of the shell when the valve is reciprocated, and guide hangers for the nozzles recipro- 100 cable on a suitable element of the boiler.

105 8. A blow off for a boiler comprising a valve casing within the boiler shell having a plurality of inlets and an outlet, suction pipes each in communication with an inlet of the casing, a closure in the casing adapted to selectively throw any one of the inlets into communication with the outlet, a valve stem rotatable and reciprocable through the boiler wall for reciprocating the casing and moving the closure, and an outlet pipe through the boiler shell having extensible 110 connections with the outlet of the valve casing.

115 9. The combination with a boiler, of a blow-off comprising a valve casing having a plurality of suction inlets and a suction outlet, a circulating inlet and a circulating outlet, suction pipes each leading from a suction inlet, suction nozzles on the pipes adjacent the interior face of the boiler shell, a circulating pipe having an intake end ad- 120

5 jacent the boiler shell and leading into the circulating inlet of the casing, an upright circulating pipe leading from the circulating outlet of the casing to the upper portion of the boiler, a single closure adapted to selectively throw each suction inlet into communication with the suction outlet and to open communication between the circulating inlet and the circulating outlet only when the suction inlets are closed, a valve 10 stem reciprocable and rotatable through the boiler shell for operating the valve closure and reciprocating the valve casing, an outlet pipe through the boiler shell and extensible connections between the outlet pipe and the suction outlet of the casing.

10. The combination with a boiler, of a blow-off comprising a valve casing having a plurality of suction inlets and a suction outlet, a circulating inlet and a circulating outlet, suction pipes each leading from a suction inlet, suction nozzles on the pipes adjacent the interior face of the boiler shell, a circulating pipe having an intake end adjacent the boiler shell and leading into the circulating inlet of the casing, an upright circulating pipe leading from the circulating outlet of the casing to the upper portion of the boiler, a single closure adapted to selectively throw each suction inlet into communication with the suction outlet and to open communication between the circulating inlet and the circulating outlet only when the suction inlets are closed, a valve 25 stem reciprocable and rotatable through the boiler shell for operating the valve closure and reciprocating the valve casing, an outlet pipe through the boiler shell, extensible connections through the outlet pipe and the suction outlet of the casing, and a fitting on the outlet end of the upright circulating pipe having a comparatively large area adapted to contact with the water of the boiler.

45 11. The combination with a boiler, of a blow-off comprising a valve casing having a plurality of suction inlets and a suction outlet, a circulating inlet and a circulating outlet, suction pipes each leading from a suction inlet, suction nozzles on the pipes adjacent the interior face of the boiler shell, a circulating pipe having an intake end adjacent the boiler shell and leading into the circulating inlet of the casing, an upright circulating pipe leading from the circulating outlet of the casing to the upper portion of the boiler, a single closure adapted to selectively throw each suction inlet into communication with the suction outlet and to open communication between the circulating inlet and the circulating outlet only when the suction inlets are closed, a valve 50 stem reciprocable and rotatable through the boiler shell for operating the valve closure and reciprocating the valve casing, an outlet pipe through the boiler shell, extensible connections between the suction pipe and the suction outlet of the casing, a guide member in the boiler parallel to the path of motion of the casing, and hangers for the nozzles reciprocable on the guide member.

110 14. The combination with a boiler, of a blow-off comprising of a valve casing having suction inlets and a suction outlet, a closure for the casing adapted by rotation to throw any one of the inlets into communication with the outlet, a valve stem reciprocable and rotatable through the wall of the casing for operating the closure and shifting the casing along the shell, suction pipes extending from the suction inlets of the casing, suction nozzles on the pipes each having an opening on its lower side surrounded by serrated margins for agitating sediment on the boiler shell, an outlet pipe through the boiler shell, extensible connections between the suction pipe and the suction outlet of the casing, a circulating intake pipe extending from a circulating inlet in the valve casing, and a circulating pipe extending upwardly from a circulating outlet in the valve casing, the 115 120 125 130

let pipe through the boiler shell, extensible connections through the outlet pipe and the suction outlet of the casing, and a fitting consisting of a spider with hollow arms secured on the outlet end of the upright circulating pipe, and a pair of concentric shells forming continuations of the spider arm walls.

12. The combination with a boiler, of a blow off consisting of a valve casing having suction inlets and a suction outlet, a closure for the casing adapted by rotation to throw any one of the inlets into communication with the outlet, a valve stem reciprocable and rotatable through the wall of the boiler 70 for operating the closure and shifting the casing along the shell, suction pipes extending from the suction inlets of the casing, suction nozzles on the pipes each having an opening on its lower side surrounded by serrated margins for agitating sediment on the boiler shell, an outlet pipe through the boiler shell and extensible connections between the suction pipe and the suction outlet of the casing.

90 13. A blow off for a boiler comprising a valve casing having suction inlets and a suction outlet, a closure for the casing adapted by rotation to throw any one of the inlets into communication with the outlet, a valve stem reciprocable and rotatable through the wall of the shell for operating the closure and shifting the casing along the boiler shell, suction pipes extending from the suction inlets of the casing, suction nozzles on the pipes each having an opening on its lower side surrounded by serrated margins for agitating sediment on the boiler shell, an outlet pipe through the boiler shell, extensible connections between the suction pipe and the suction outlet of the casing, a guide member in the boiler parallel to the path of motion of the casing, and hangers for the nozzles reciprocable on the guide member.

100 14. The combination with a boiler, of a blow-off comprising of a valve casing having suction inlets and a suction outlet, a closure for the casing adapted by rotation to throw any one of the inlets into communication with the outlet, a valve stem reciprocable and rotatable through the wall of the casing for operating the closure and shifting the casing along the shell, suction pipes extending from the suction inlets of the casing, suction nozzles on the pipes each having an opening on its lower side surrounded by serrated margins for agitating sediment on the boiler shell, an outlet pipe through the boiler shell, extensible connections between the suction pipe and the suction outlet of the casing, a circulating intake pipe extending from a circulating inlet in the valve casing, and a circulating pipe extending upwardly from a circulating outlet in the valve casing, the 105 110 115 120 125 130

valve closure being adapted to throw the circulating inlet into communication with the circulating outlet only when the suction inlets are each closed.

- 5 15. The combination with a boiler, and a guide member along the shell thereof within the boiler, of a valve casing in the shell having a series of suction inlets and a suction outlet, a valve closure in the casing
10 adapted to throw each of the inlets into communication with the suction outlet, a set of suction pipes extending for various distances each from an inlet of the casing, a suction nozzle on each pipe, hangers for
15 the nozzles traveling on the guide member, a valve stem reciprocable and rotatable through the boiler shell for operating the closure and reciprocating the casing, a cir-

culating inlet pipe carried by the casing, a circulating outlet pipe carried by the casing, the closure being adapted to throw said circulating pipe into communication when the suction inlets are all closed, said casing and pipes comprising a unitary structure bodily reciprocable within the boiler shell by means of the closure stem from a point without the shell, a suction outlet pipe through the shell, and flexible connections between the outlet pipe and the suction outlet of the casing.

In testimony whereof I affix my signature in presence of two witnesses.

GEORGE PURVIS.
